UNITED STATES PATENT OFFICE.

JOSEPH POLIVKA, OF CHICAGO, ILLINOIS.

COLLAPSIBLE FURNITURE.

Application filed January 20, 1922. Serial No. 530,534.

To all whom it may concern:

Be it known that I, JOSEPH POLIVKA, a citizen of the United States, residing at Chicago, in the county of Cook and State of Illinois, have invented a new and useful Improvement in Collapsible Furniture, of which the following is a specification.

This invention relates to collapsible or folding furniture and has particular reference to collapsible chairs and tables.

It is an object of this invention to provide a chair or table which shall be collapsible or folding and arranged to occupy a minimum of space.

15 The invention also contemplates among its objects, the construction of a chair or table which includes a plurality of simple members adapted for folding one into the other.

20 With these and other objects in view my invention consists in the novel construction, combination and relative position of the parts and members hereinafter described and shown in the accompanying drawings, 25 and particularly pointed out in the appended claims.

Referring to the drawing in which like reference characters indicate like or corresponding parts:

30 Figure 1 is a side elevation of a chair embodying my invention and shown in unfolded or extended position.

Figure 2 is a plan view of Figure 1 with the seat portion partly broken to show details of other members.

35 Figure 3 is a view of Figure 1 in the collapsed or folded position.

Figure 4 is an enlarged top view of Figure 3.

40 Figure 5 is an enlarged detail of the pivotal connection for the strut and brace members showing their abutment with a centrally mounted retaining member.

45 Figures 6 and 7 illustrate respectively elevation and plan views of a modification of my invention showing a chair or table embodying four supporting legs each arranged in two pivoted sections the lower sections being movable outwardly and over the upper sections into folded position as shown by Figure 8.

50 Figure 8 shows the chair illustrated in Figs. 6 and 7 in folded position.

55 Figure 9 is an enlarged detail of the central retaining member and pivotal connection for struts and braces.

Figure 10 illustrates the abutment of the knee-brace with the upper leg member and also the abutment of the lower leg member with the knee-brace and the upper leg member.

Referring now particularly to Figures 1 to 5 inclusive, the construction here shown includes a top or seat 10 forming substantially an equilateral triangle which may be 60 made of any suitable flexible material such as canvas, the edges thereof being supported on the flexible members or rope 11. The flexible members 11 are supported at their ends in the tops 12^A of the legs 12 which are 65 substantially of U or channel cross section. The lower ends of these legs 12 are slightly flared downwardly and outwardly at 12^B to afford connection for the tie bars 13 which are pivoted at 13^A and provided with a 70 hinge at 13^B. The legs 12 are also formed with laterally and inwardly disposed integral feet 12^C.

When the chair is in extended position as shown in Figure 1, the knee braces 14, which 75 are of channel cross section, extend upwardly at approximately an angle of 30° from their lower pivotal point 15 intermediate each channel leg to their upper pivot 16 about the extending integral ear 17^A of the 80 central retaining member 17. It will be noted that the knee braces 14 are slightly narrower in width than the distance between the sides of the channel legs to permit folding there between as will be described later. To complete the triangular 85 supporting frame, an inverted U or channel shaped strut 18 is provided to cooperate with each leg and brace 14. These struts 18 are slightly narrower in width than the 90 space between the sides of the U-knee brace 14 and are also pivoted about the pin 16. A suitable spring 19 tends to retain the separated or spread position of the strut 18 95 from the knee brace 14. The maximum upward movement of the strut 18 is fixed by the engagement of the right angular or straight ends 18^A with the abutment faces 17^B of the retaining member 17. Likewise the angular inclination of 30° for the braces 14 is fixed by the engagement of their straight ends 14^A with the abutments 17^B.

100 Likewise the angular inclination of 30° for the braces 14 is fixed by the engagement of their straight ends 14^A with the abutments 17^B. The free ends 18^B are cut at right angles for abutment within the channel legs. It is thus obvious that the legs 12 are rigidly 110 supported by opposed triangular frames formed by a strut and brace cooperating

with each leg and that all frames have a common central abutment member 17.

To attain the folded position illustrated by Fig. 3, the struts 18 are depressed (as shown by arrows in Fig. 1) against the pressure of the springs 19 into and between the sides of the braces 14 which are simultaneously moved upwardly (as shown by arrows in Fig. 1) into and between the sides 10 of the upper portion of the channeled legs 12. During such movement, the tie bars 13 are folded upwardly between the legs as clearly shown in Fig. 3.

Referring now to Figs. 6 to 9 inclusive, this structure involves the principles and details of construction substantially as above described; the modification appearing in the four leg construction whereby the common central abutment or retaining member 20 is of square instead of triangular design. The table or chair is also made higher by the provision of two part leg including an upper member 21 and a lower member 22 which is pivoted at 15 and reversely mounted to permit an outwardly and upward movement for folding over the outside of the portions 21 as shown in Fig. 8. It is obvious that the channeled lower portions 22 must be wider than the outside width of the upper portions 21 and that if the lower members 22 are longer than the upper as here shown, the space between the top 21^A of the upper members and the feet 22^B of the lower members, when in folded position as shown in Fig. 8, can be utilized for concealment and carrying of the seat on top 23. The small rope ties 24 prevent the outward spreading of the legs.

Further inward movement of the leg portions 22 about the pivot 15 is overcome by the engagement of the overlapping cut 22^B over the edges 21^B.

The principles of design and construction herein described and shown in the accom-

panying drawings can thus readily be applied to chairs or tables of three or more legs and the same can be made in various heights and dimensions.

I claim:

1. An article of the kind described, comprising a flexible member forming substantially an equilateral triangle, a supporting leg of channel cross-section for each corner of said member, a brace of channel cross-section pivoted intermediate each of said legs and inclined upwardly toward its upper pivotal end, a member forming a common pivotal support for said upper ends of said braces, and struts extending from and pivoted only at said common pivotal support and having a square abutment with said leg, said struts and braces being relatively fixed and pivotally mounted to said common pivotal support and movable with it and adapted when in folded position to lie within said channeled legs.

2. In an article of the kind described, the combination of a plurality of channeled legs, a brace and strut for each leg extending from the leg toward the center of the article and being relatively fixed to and movable with a common abutment member, said braces being angularly disposed to said struts, the struts being arranged for folding within said braces, and said braces within said channeled legs, and a flexible cover member extending over the top of said legs, said braces being provided at their lower pivotal ends with an abutment shoulder arranged to engage the inner side of the leg to limit their angle of inclination when in open position, and said struts having a right-angular end face for square abutment with the leg.

In witness whereof, I have hereunto subscribed my name this 16th day of January, 1922.

JOSEPH POLIVKA.
